DESIGN FOR A CANDY BOX OR THE LIKE

Samuel A. Cohen, Brighton, Mass.

Application May 27, 1935, Serial No. 57,036

Term of patent 7 years

To all whom it may concern:

Be it known that I, Samuel A. Cohen, a citizen of the United States, residing at 192 Chiswick Road, Brighton, in the county of Suffolk and Commonwealth of Massachusetts, have invented a new, original, and ornamental Design for Candy Boxes or the like, of which the following is a specification, reference being had to the accompanying drawing, forming part thereof, in which

Figure 1 shows a front view of the box embodying my new design, and Figure 2 shows a perspective, looking diagonally at the top of the box.

I claim:

The ornamental design for a candy box or the like, substantially as shown.

SAMUEL A. COHEN.
